(57) **CLAIM**

The design for the bag, as shown and described.

DESCRIPTION

FIG. 1 is a left side view of the bag showing my new design.

FIG. 2 is a right side view thereof.

FIG. 3 is a top view thereof.

FIG. 4 is a bottom view thereof.

FIG. 5 is a front view thereof; and,

FIG. 6 is a rear view thereof.

The broken line showing of a circular detail in FIG. 3 is included for the purpose of showing environmental portions of the bag and forms no part of the claimed design.
